UNITED STATES PATENT OFFICE.

EDOUARD P. BENOIS, OF PARIS, FRANCE, ASSIGNOR TO COTY, INC., OF NEW YORK, N. Y.,
A CORPORATION OF DELAWARE.

DESIGN FOR A BOTTLE.

Application filed May 3, 1923. Serial No. 6,043. Term of patent 14 years.

To all whom it may concern:

Be it known that I, EDOUARD P. BENOIS, a citizen of France, residing in the city of Paris, Republic of France, have invented a new, original, and ornamental Design for a Bottle, of which the following is a specification, reference being had to the accompanying drawing, forming a part thereof.

In the drawing,

Figure 1 is a perspective view of my bottle, and

Figure 2 is a top view thereof.

I claim:—

The ornamental design for a bottle substantially as shown.

EDOUARD P. BENOIS.
